[57] CLAIM

The ornamental design for a crutch, as shown and described.

DESCRIPTION

FIG. 1 is an environmental perspective view of a crutch showing our new design;

FIG. 2 is an environmental left side elevational view thereof;

FIG. 3 is a front elevational view thereof;

FIG. 4 is a rear elevational view thereof;

FIG. 5 is a right side elevational view thereof;

FIG. 6 is a top plan view thereof;

FIG. 7 is a bottom plan view thereof; and,

FIG. 8 is a right side elevational view thereof with the end cap removed.

The broken line showing of the removable padding in FIG. 1 and the human figure in FIG. 2 is for illustrative purposes only and forms no part of the claimed design.
